FIRE ESCAPE

Edward J. McConologue, San Francisco, Calif.

Application August 28, 1956, Serial No. 606,644

2 Claims. (Cl. 182—85)

This invention relates to a fire escape.

The primary object of this invention is to provide a fire escape with a collapsible fire escape ladder of a lazy-tong type.

Another object of this invention is to provide a fire escape ladder of the type described which is particularly stable, light and easily extended and contracted.

Another object of this invention is to provide a fire escape ladder in which the sides of the same are made of pivoted links arranged on a lazy-tong principle and having the top pair of said links on each side considerably longer than the rest of the links to provide greater lateral stability for said ladder.

Another object of this invention is to provide an efficient and simple brake for said ladder which permits the expansion of said ladder at a desirable uniform speed.

Other objects and advantages will appear as the specification proceeds and the novel features of the device will be particularly pointed out in the claims hereto annexed.

In this specification and the annexed drawing, the invention is illustrated in the form considered to be the best but it is understood, that the invention is not limited to such form; and it is also to be understood that in and by the claims following the description, it is desired to cover the invention in whatsoever form it may be embodied.

This invention is illustrated in the accompanying drawings, forming a part of the specification, wherein:

Fig. 1 is a side view of the fire escape.

Fig. 2 is a front view of said fire escape.

Fig. 3 is a side view of said fire escape with the ladder in a contracted position.

Fig. 4 is a plan view of said fire escape.

Fig. 5 is a cross-section of Fig. 1 on the line 5—5.

Fig. 6 is a perspective view of a slide plate attached to a beam.

Fig. 7 is a partial perspective view of a modified form of the attachment of the ladder to the fire escape balcony.

The fire escape, comprising the subject matter of this invention consists of a ladder 1 which is secured to a usual escape balcony 2. The latter includes floor beams 3, covered with planks 4, and a railing 5 with upper beams 7, to which said ladder is secured in a manner to be hereinafter described in detail.

The ladder 1 consists of two sides 10 and 11, connected by rungs 12. Each of said sides is constructed on the lazy-tong principle and is formed of a plurality of links 14 and 15 pivoted at their middles by said rungs 12. The ends of said links 14 are pivoted to the ends of the links 15, as shown at 17. All the links 14 and 15 are of the uniform length. However, a pair of the top links 20 and 21 of each side 10 and 11 is considerably longer, preferably one and a half times longer than the links 14 and 15. Each of the links 20 and 21 is divided by a rung 12, by which they are pivoted together, into two unequal portions: a lower portion 24 and an upper portion 25. The lower portion 24 is equal

2

to one half the length of the link 14 and 15, while the upper portion 25 is preferably twice the length of the lower portion 24. The longer top links 20 and 21 provide considerably greater lateral stability for the ladder 1 while the same is used.

The ladder 1 is secured to the balcony 2 in the following manner: A pair of slide plates 28 is secured by welding, or otherwise, to the top of each upper beam 7. Each of said slide plates is provided with an elongated opening 30. The upper ends of the top links 20 and 21 carry studs 31 secured thereto, which studs pass through said openings and are free to slide therein. The free ends of said studs pass beyond the plates 28 and are reduced in diameter at 32 and threaded, and carry washers 33 and nuts 34 locking said studs in said openings. The studs 31 are free to slide in said openings 30. When the ladder 1 is extended, as shown in Fig. 1, the studs 31 occupy the closest position to each other. When the ladder is contracted, the studs 31 occupy the farthest position from each other.

An elongated metal guard plate 36 is secured to said beams 7 and 3 at each side of the ladder in the middle between said plates 28, which guard plate extends downwardly from the beam 7 to the beam 3 and some distance beyond the latter beam and has its lower end flared outwardly and away from the ladder 1. The guard plates 36 are provided to prevent direct contact of the links 14 and 15, 20 and 21, with the beams 3 and other parts of the balcony 2, in order to bar possible entanglement of said links with the balcony, and to assure proper extension and contraction of the ladder 1.

The ladder 1 generally is stored on the balcony 2 in a contracted position, as shown in Fig. 3. It may be extended to the ground in a few seconds and raised into a contracted position by a mechanism presently to be described.

The upper beams 7 carry secured thereto supports 40 in which a shaft 41 is journaled. The latter carries a drum 42 having a rope 43 wound thereon. Both ends of the shaft 41 are squared for the purpose of placing a handle 45 on either of them for rotating said shaft and drum.

The shaft 41 also carries a cog-wheel 46 thereon which serves as a lock as it will be hereinafter explained.

Another shaft 50 having a drum 51 is arranged in close vicinity to said ladder 1 and parallel to the shaft 41. The shaft 50 is rotatably supported in brackets 53 secured to said beams 7. The rope 43 of the drum 42 extends to the drum 51 and is wound about said drum a few times and is further extended to the first rung 12 and over the same downwardly to the last rung 12 to which the end of the rope 43 is secured. By rotating the shaft 41, the rope rotates the drum 51 and the shaft 50 and the ladder 1 is gradually collapsed and brought into an upward position, as shown in Fig. 3.

One of the brackets 53 carries a lever 55 pivotally secured thereto above the shaft 50. The lever 55 carries on one of its ends a loop 56 which normally extends to the cog-wheel 46 and engages one of the cogs 47 thereon. The other end of said lever 55 is formed into a handle 57.

When the ladder 1 is in a contracted position, the loop 56 is on one of the cogs of the cog-wheel 46 and thus keeps said shaft 50 arrested, and by means of the rope 43 also keeps the ladder 1 suspended in the contracted position.

To release the ladder 1, the lever 55 is swung in a counterclockwise direction. This releases the cog-wheel 46 from the loop 56. The weight of the ladder 1 pulls the rope 43 downwardly at an ever increasing speed.

The rope 43 forces the drums 51 and 42 with their respective shafts to rotate. The inertia and the friction

of said drums and shafts slows down the expansion of the ladder 1 to a desired speed.

Fig. 7 shows a modified form of connection between the ladder 1 and the balcony 2 in which the openings 30a are cut directly in the beam 7a.

Instead of the shaft 50 and the drum 51, some other means may be used for the purpose of stabilizing and braking the descent of the ladder 1 and for centering the downward movement of the rope 43.

I claim:

1. The combination with a fire escape balcony having upper beams and floor beams, of a fire escape ladder comprising two sides, a plurality of rungs connecting said sides; each of the sides consisting of a pair of uppermost long links, and a plurality of short links secured to each other on a lazy-tong principle, said long links being at least one and a half times longer than the short links; means for slidably securing the top ends of said long links to the upper beams, a first shaft rotatably secured to said upper beams, a first drum secured to said first shaft for rotation therewith; a second shaft secured to said upper beams, a second drum carried by said second shaft; a rope attached to the first drum, said rope extending to the second drum and wound therearound, and further extending to the lowermost rung and having its end attached thereto; a cog-wheel secured to the first shaft, means for engaging said cog-wheel for arresting the rotation of the shaft, and for releasing said cog-wheel; means for rotating the first shaft for winding said rope on the first drum, and thus collapsing and raising said ladder, said rope, drums and shafts acting as a brake when the ladder expands downwardly.

2. The combination with a fire escape balcony including floor beams covered with planks and a railing around the balcony reinforced with upper beams; of a fire escape ladder comprising two sides, each side con-

sisting of a pair of uppermost long links and a plurality of short links secured to each other on a lazy-tong principle, said long links being at least one and a half times longer than the short links; a plurality of rungs connecting said sides, each rung passing through a pair of the links and serving as a pivot thereto; said upper beams having slots arranged therewith; a stud carried by the upper end of each of the top links, each of said studs passing through a respective slot and slidably retained therein; said slots being so spaced from each other that when the studs contact the inner ends of the slides, the end of the ladder reaches the ground; a first shaft rotatably secured to said upper beams, a first drum secured to said first shaft for rotation therewith; a second shaft secured to said upper beams, a second drum carried by said second shaft; a rope attached to the first drum, said rope extending to the second drum and wound therearound, and further extending to the lowermost rung and having its end attached thereto; a cog-wheel secured to the first shaft, means for engaging said cog-wheel for arresting the rotation of the shaft, and for releasing said cog-wheel; means for rotating the first shaft for winding said rope on the first drum and thus collapsing and raising said ladder, said rope, drums and shafts acting as a brake when the ladder expands downwardly.
